Primary Examiner—Celia Murphy(74) *Attorney, Agent, or Firm*—Blackwell Sanders Peper Martin LLP(57) **CLAIM**

The ornamental design for a shoe sole, as shown and described.

DESCRIPTION

FIG. 1 is a perspective view of a shoe sole showing our new design;

FIG. 2 is a front elevational view thereof;

FIG. 3 is a rear elevational view thereof;

FIG. 4 is a side elevational view thereof; the opposite side being a mirror image; and,

FIG. 5 is a bottom plan view thereof.

The new design is for a shoe sole that is to be used on toy stuffed animals, such as teddy bears. The broken line showing a shoe upper in FIG. 1 illustrates a portion of a possible environment for the shoe sole, but forms no part of the claimed design. The surfaces which are not shown, form no part of the claimed design.
